COMBINATION DISPOSABLE TOOTHBRUSH AND RECEPTACLE THEREFOR

Ted R. Fuskarcik, Campbell, Ohio, assignor of fifty percent to William P. Gale, Hubbard, Ohio

Filed June 18, 1969, Ser. No. 17,758

Term of patent 14 years

Int. Cl. D4—02; D9—04

U.S. Cl. D4—18

FIG. 1

FIG. 2

FIG. 3

FIG. 5

FIG. 1 is a side elevation of the disposable toothbrush and paste appliance showing my new design;

FIG. 2 is a back plan view thereof; and

FIG. 3 is a front plan view thereof; the opposite side not shown is a mirror image of FIG. 1.

FIG. 4 is a front elevation of a second modified embodiment of receptacle illustrated in FIG. 1, the difference residing in the front brush cover; and

FIG. 5 is a third modified embodiment of the receptacle illustrated in FIG. 1.

I claim:

The ornamental design for a combination disposable toothbrush and receptacle therefor, as shown and described.
